PORTRABLE BAR

Daniel L. Weaver, 3710 N. Meridian St.,
Indianapolis, Ind. 46208

Filed Feb. 3, 1975, Ser. No. 546,436

Term of patent 14 years

Int. Cl. D6—04

U.S. Cl. D6—144

Fig. 1

Fig. 2

Fig. 3

Fig. 4

Fig. 5

Fig. 6

FIG. 1 is an elevational view of a portable bar showing one of the four identical sides of my design.

FIG. 2 is a top plan view thereof.

FIG. 3 is a side elevational view of the portable bar of FIG. 1 but wherein the four support columns have been modified.

FIG. 4 is a top plan view thereof.

FIG. 5 is a side elevational view of the portable bar of FIG. 1 but wherein the four support columns have been further modified.

FIG. 6 is a top plan view thereof.

The top surface of the cabinet portion and the under-surface of the top of the bar are both conventionally flat and unornamented.

I claim:

The ornamental design for a portable bar, as shown and described.
